WELL PUMPING EQUIPMENT

William J. Gourley and Fred H. Barney, Fort Worth, and Edward E. Goehring, Henderson, Tex.

Original application December 15, 1933, Serial No. 702,548. Divided and this application February 17, 1936, Serial No. 64,358

5 Claims. (Cl. 74—522.5)

This invention relates to new and useful improvements in well pumping equipment.

This application is filed as a divisional application of my original co-pending application filed December 15, 1933, Serial No. 702,548.

One object of the invention is to provide pumping equipment wherein an improved swing is employed for transmitting motion from a pumping power to a rod line.

10 An important object of the invention is to provide an improved swing beam for transmitting motion from a pumping power to a rod line which is arranged so as to reduce rod line vibration to a minimum, and which is so constructed that transmission ratios may be set up for controlling the length of the stroke or travel of the rod line.

Another object of the invention is to provide an improved swing beam wherein the supporting bearing, as well as the bearings to which the pitman and rod line are connected are constructed so as to insure constant lubrication and to withstand heavy loads, as well as being substantially dust and water proof.

25 A further object of the invention is to provide an improved swing which is capable of pumping two wells at the same time and which is so designed that the well to be pumped or operated can be located at most any angle with relation to the pumping power, thereby making it unnecessary for said well to be in direct line with said power.

Still another object of the invention is to provide an improved swing which is adapted to be connected with the usual pitman of a pumping power and operated by a push and pull motion, the swing having means whereby a suitable "knock-off" or disconnecting device may be connected therewith.

30 A construction designed to carry out the invention will be hereinafter described, together with other features of the invention.

The invention will be more readily understood from a reading of the following specification and by reference to the accompanying drawings, in which an example of the invention is shown, and 45 wherein:

Figure 1 is a plan view of a swing beam constructed in accordance with the invention.

Figure 2 is a side elevation of the same.

Figure 3 is a vertical, sectional view of the swing bearing and support, and taken on the line 3—3 of Figure 1.

Figure 4 is a transverse, vertical, sectional view taken on the line 4—4 of Figure 1.

Figure 5 is a vertical, sectional view, taken on the line 5—5 of Figure 4.

Figure 6 is a plan view (details omitted) showing the swing connected with a pumping power and rod line,

Figure 7 is a view, partly in section and partly in elevation of a modified form of the swing, and 5

Figure 8 is a transverse, vertical sectional view, taken on the line 8—8 of Figure 7.

In the drawings, the numeral 10 designates a pumping power (Figure 6) which may be of any suitable type. The usual pitman 11 has one end pivoted to the eccentric ring 12 of said power. It is customary to provide a shelf or rail 13 on which the pitman may rest when it is disconnected from the swing. The loop 14 at the other end of the pitman is connected to a hook 15 carried by a 15 swing beam 16 which is mounted to swing on a post 17.

The hook 15 is attached to a bearing collar 18 mounted in the beam (Figures 1, 4 and 5). A second bearing collar 19 also mounted in the beam is 20 connected through a suitable "knock-off" or disconnecting device 20 with a rod line 21. The rod line has connection with the usual pump jack (not shown). The pump rods in the well exert a pull on the rod line 21 which pull is applied to the 25 parts attached thereto and transmitted back to the power 10. With the hook-off 20 connecting the rod line with the swing, the pull exerted by the power 10 through the pitman is transmitted to the rod line. With the hook-off device disengaged, the motion from the pumping power will 30 not be transmitted to the rod line 21. It is noted that the pumping power and hook-off device 20 form no part of the present invention, the latter being fully described in our co-pending application filed December 15, 1933, Serial No. 702,548. In fact it would be possible to eliminate the hook-off entirely and connect the rod line 21 directly to the bearing 19. 35

The swing beam 16 is formed of top and bottom channels 22 and 23, the upper one being inverted so that their flanges are inwardly opposed and spaced apart. These channels are provided with bolt holes 24 and 25. The bearing 18 is secured by bolts through the bolt holes 24 and this bearing includes a bearing cap 26 which is fastened to the top channel 22 of the beam by bolts 28' which pass through the openings 24 in said channel. A bearing step 27 is secured to the lower channel in a similar way by bolts 27' which pass through the 50 bolt holes 24 in said lower channel. The bearing 18 is completed by a central collar 18' located and confined between the cap 26 and step 27. This collar has a central well 28 which receives a pivot stud 29 depending from the cap. A stud 30 55

depends from the collar into a well 31 in the step. The studs are hollow and the wells co-acting therewith will hold ample quantities of lubricant. Any suitable means for supplying lubricant to the wells may be employed.

As is clearly shown in Figure 1, the bolt holes 24 are spaced substantially throughout the length of the channel bars 22 and 23. Thus, by removing the bolts 26' and 27', the bearing 18 may be moved longitudinally of the channel bars. Thus, its position with relation to the pivot point of the beam which is the post 17 may be varied. The additional spaced bolt holes 24 permit the bearing to be fastened in the beam in any position therealong. When the position of the bearing 18 which is connected with the pumping power 10 is varied along the length of said beam, it will be obvious that the swing of the beam will be varied, whereby the movement or stroke of the rod line 21 will be varied. Therefore, by properly adjusting the bearing 18 within the beam, the desired length of stroke of the rod line may be had.

The bearing 19 to which the rod line 21 is attached includes a cap 32 which is secured to the upper channel 22 by bolts 33 which extend through the bolt holes 25. A step 34 is fastened to the lower channel 23 by bolts 35 which pass through the bolt holes 25 in this lower channel. A bearing collar 19' is located between the cap and step and is confined therein by a hollow stud 37 which depends from the cap 32 into the central well 38 of the collar. The collar has a depending hollow stud 39 depending into the well 40 of the step 34. A rod 41 by which connection may be made with the bearing 19 extends transversely through the collar 19'. Thus, it is seen that the bearings 18 and 19 are similar in construction.

The bearing collars 18' and 19' have flanged bearing contacts with their caps and steps, which contacts may be suitably packed whereby escape of the lubricant from the wells of the bearings is reduced to a minimum. The bearing contacts are large and the oil baths make for adequate lubrication and cool journals. Further, it is noted that the packing at the contacts not only prevents escape of lubricant but also makes the bearings substantially dust and water proof.

For supporting the inner end of the beam 16 on the post 17 so that said beam may undergo a swinging movement, a bearing member is provided. This member includes a bearing step 43 fastened to the post by U-bolts 44 (Figure 3). A hub 45 is journaled between the step 43 and a cap 46 which is held on the post by U-bolts 47. The hub is formed with brackets 48 which extend contiguous to the channels 22 and 23 of the beam, being secured to said channels by bolts 49. This bearing member is of the oil bath type and is similar to the bearings 18 and 19. The step has a well 43' which receives a hollow stud 44' depending from the hub. The upper end of the step fits in the bottom of the hub around the stud. The upper end of the hub engages in the bottom of the cap 46 around a stud 46' which depends into a well 45' in the hub. The joints may be suitably packed and lubricating oil may be constantly fed to the wells 45' and 43'. The bearing members are large and adequate to support the beam.

From the above, it will be seen that a most rigid swing beam is had. All bearings are provided with an oil bath and are substantially water and dust proof. Because of the bearing adjust-

ment on the beam 16, whereby the bearing 18 may be shifted to amplify or reduce the swing of said beam and the travel of the connecting rod and the rod line which is coupled thereto, a number of operations may be carried out. When the standing valves become clogged with sand, the stroke can be lengthened to strike the valves together and jar loose the sand, or the top of a corroded working barrel may be cleaned by changing the stroke. The swing may be worked at an angle and more than one well can be operated thereby. Because of the easy swing a smaller rod line may be employed. Two wells may be pumped by the same swing, one with a long stroke and the other with a short stroke. The beam 16 may be mounted high above the ground or close to it, as the case may be.

When the pumping is to be stopped, the operator merely has to wait until the beam swings to the right (Figure 1) to complete its pull stroke, and then uncouple the rod line 21 by disengaging the hook-off device 20. The beam 16 may continue to swing; however, where the hook 15 is used, the pitman will push its loop 14 out of said hook, thus riding on the shelf 13 and save the swing from unnecessary wear.

While the connection to the pitman 11 is shown by means of the hook 15 and loop 14, whereby the parts are automatically disconnected it is to be understood that any desirable connection between the pitman and bearing 18 may be made, and the automatic disconnecting feature may be eliminated.

It is pointed out that because of the proximity of the swing beam 16 to the pumping power 10, the amplitude of swing of said beam is not as great, for a given rod line stroke, as where the swing beam (usually vertical) is located at a considerable distance from the pumping power, which is the present oil field practice. By shortening the arc of the beam travel, lateral movement or side play in the post 17 is greatly reduced. This not only cuts down vibration and side whip, but reduces wear of the parts and makes for an easy operation.

In Figures 7 and 8, another means for adjusting the collar bearing 18 is shown. The cap 26 is arranged to slide longitudinally of the beam 16 on one side of a track 50; while the step 27 is mounted to slide on one side of a track 51. A bottom worm screw 52 is journaled in hangers 53 and threaded through an ear 54 on the adjacent side of the step 27. This screw has its head projecting from the outer end of the beam. By turning the screw 52 the collar 18 is adjusted longitudinally of the beam. Any other form of adjustment may be used.

What we claim and desire to secure by Letters Patent, is:

1. A swing for well pumping equipment including, a post, upper cap and lower step supporting brackets on the post, a beam comprising spaced top and bottom members, a hub member to which said beam members are respectively connected at one end, said hub member having a depending open-ended hollow stud at its lower end received and working rotatably in a well provided therefor in the lower bracket step member on said post and its upper portion provided with a well, the upper bracket cap member on the post having a depending open-ended hollow stud received and working rotatably in said well of the hub member, and power transmission connecting bearings between said beam members each comprising a cap member located on the

under side of the top beam member and having a depending open-ended hollow stud, an opposed step member located on the upper side of the bottom beam member and having a well therein, and a collar member for the attachment of a power transmission element interposed rotatably between said cap and step members, said collar having an open-ended hollow stud at its lower end fitted rotatably in the well of said 5 step member and a well in its upper portion in which the stud of said cap member is rotatably fitted, said beam-supporting hub member and said bearing collars each having a peripheral flanged annular interfitting bearing contact at 10 their ends with the respective upper cap and lower step members.

2. A swing for well pumping equipment including, a post, a beam hingedly supported at one end on said post, and a bearing member on said 20 beam intermediate the ends thereof for the attachment of a power transmission element, said bearing member and the hinge element of the beam each comprising an upper cap member, a correlated lower step member and a collar member 25 interposed between each of said cap members and the correlated step member, the respective step members each having a well in its upper portion, the associated collar member having a well in its upper portion and provided with a 30 depending axially aligned open-ended hollow stud received and working rotatably in the well of the step member, and the correlated cap member having a depending axially aligned open-ended hollow stud received and working rotatably in 35 the well of said collar member, the ends of said collar members having peripheral interfitting flanged annular bearing contact with the respective cap and step members.

3. A bearing for the purpose described, comprising, an intermediate substantial-bodied collar member having an axial circular well in its upper portion and a depending axial open-ended hollow stud at its lower end, a step member having an axial well in its upper portion receiving 40 the stud of said collar member rotatably therein, and a cap member having a depending axial 45

open-ended hollow stud received rotatably in the well of said collar member, the ends of said collar member having peripheral interfitting flanged annular bearing contact with said step member and said cap member, but otherwise 5 free from contact with said members.

4. A swing beam for well pumping equipment comprising, a spaced pair of elongate channel members pivotally supported in fixed parallel relation to each other at one end, longitudinal 10 trackways on the opposed inner sides of said channel members at one side of the longitudinal axis of the beam, a power connection journal element including end members mounted movably in said trackways and an intermediate connector member having annular rotatable engagement at its opposite ends with said end members, means for adjusting and holding said power connection journal element in said trackways longitudinally of the beam, and a pump 15 jack rod line connection element of construction similar to said power connection journal element secured between said channel members at the side of the longitudinal axis of the beam opposite to said trackways.

25 5. Well pumping equipment including, an upright rigid post, upper and lower bearing members rigidly attached to one side of the upright post, a horizontal swing beam having upper and lower bearing elements at its inner end rotatively engaging the bearing members, whereby said beam is free to swing in a horizontal arc, a journal bearing for a pump rod connection mounted on the beam at one side of the median longitudinal line thereof, and a power connection 30 journal bearing mounted on the beam on the opposite side of said median longitudinal line thereof, said power connection journal bearing being adjustable longitudinally of the beam to vary the swing amplitude of the beam and being 35 free from connection with the bearing members and elements on which the beam is mounted.

WILLIAM J. GOURLEY.
